UNITED STATES PATENT OFFICE.

LOUIS HUBERT WILLEM REGOUT, OF MAESTRICHT, NETHERLANDS.

MUFFLE FURNACE OR OVEN.

SPECIFICATION forming part of Letters Patent No. 653,819, dated July 17, 1900.

Application filed November 9, 1899. Serial No. 736,412. (No model.)

To all whom it may concern:

Be it known that I, LOUIS HUBERT WILLEM REGOUT, engineer, a subject of the Queen of the Netherlands, residing at Stationstraat 32, 5 Maestricht, in the Kingdom of the Netherlands, have invented certain new and useful Improvements in or Relating to Muffle Furnaces or Ovens, of which the following is a specification.

10 The present invention relates to a muffle furnace or oven for continuous working with direct base-firing.

In the ordinary annular muffle-furnaces a direct base-firing is properly not possible, owing to the arrangements of the wheels required for the movement of the rotating annular plate underneath the muffle and because this annular plate forms at the same time the bottom of the muffle.

20 The present invention refers to muffle furnaces or ovens in which direct base-firing is made possible, while continuous working by means of an annular plate or support is not interfered with. For this purpose the bottom of the muffle is solid and in every part constructed of fire-resisting material, with a few small openings at intervals, from which project cast-iron rollers for the rotating bottom plate or support. These rollers, however,

25 are not placed directly over the fire-space. The furnace consists of an annular passage the dimensions of which depend on the material to be treated. A part of the furnace—*i. e.*, the muffle—in which the burning process is carried out is directly heated, and this part is constructed entirely of fire-resisting stone or material. The parts which serve, respectively, for the preliminary heating and for the cooling of the articles after burning are

30 preferably constructed partly of fire-resisting material and partly of metal. The fire from the grate comes in direct contact with the bottom of the muffle. The heating-gases ascend by way of lateral passages and surround the muffle before they are allowed to escape through the chimney.

The muffle-furnace is provided with a continuous rotary bottom arranged a little above the bottom of the muffle. This traveling surface is supported on iron rollers and consists of a grating of cross bars or plates, on which the articles to be treated are placed. By ro-

tating the traveling support the articles pass first through the space where the preliminary heating is effected, then through the muffle, 55 and afterward through the cooling - space, from which they pass on and return to the original position and can be removed from the furnace.

The new muffle-furnace is represented in 60 the accompanying drawings.

Figure 1 is a plan view, partly in section, of the muffle-furnace; and Fig. 2, a vertical section through the furnace at the firing-place, but on a larger scale than Fig. 1. 65

The annular furnace *o* consists of a section BC, which is exposed directly to the strong fire, and consequently is constructed exclusively of fire-resisting material, two sections AB and CD, adjoining the firing-section, which 70 are exposed to a less-intense heat and are also constructed of fire-resisting material, the section DE before the preliminary-heating section DC, and which is made of sheet-iron or plates, as well as the section AF for the cooling, and finally of a section FE, which is left 75 open. The section EF serves for the introduction and removal of the charge of the articles to be treated. The next two sections ED and DC serve for the preliminary heating, the next section BC for the burning, and the next two, BA and AF, for the cooling 80 of the articles treated. The firing space or grate *a* is beneath the muffle *g*, Fig. 2. The flames produced on the grate-bars *b* come in 85 contact directly with the bottom *c* of the muffle. The heating - gases then ascend through passages *d* on both sides of the chamber into the space *e* above the muffle and envelop completely the surface of the muffle 90 up to the chimney *f*, passing through the passages *t*, Fig. 1, which are arranged around the muffle, and finally escaping by the chimney. In the annular furnace there is an annular 95 bottom plate or support comprising steel rails or bars *h*, which are connected at intervals by ties or rods *i* and covered with bars or plates *n*. The steel rails are supported on rollers *k*, which are mounted on axles *l*, which are capable of rotation in stationary bearings *m* and are so arranged that the axles and bearings are not exposed to the heat of the fire. The rotatory annular bottom support extending through the whole

100

furnace is thus produced. On this traveling support are placed the articles to be treated, bars or guards *p*, Fig. 2, being arranged at the sides to protect the articles from falling over. The traveling support, together with the articles standing on it, is then moved onward by means of toothed-wheel gearing *q*, Fig. 1. The bottom *c* of the muffle *g* is solid and constructed of fire-clay plates, and there are only in a few places at intervals small passages or recesses through which the rollers *k* project into the heating and cooling spaces *AB*, *BC*, and *CD*. As shown in Fig. 1, these recesses are absent from the upper part of the fire-chamber *a*. The operation is as follows: After the articles to be treated have been placed in the part *FE* on the supporting-surface they are introduced in consequence of the rotary movement imparted to it first into the part *DC* of the furnace, which is not directly heated, where they are preliminarily heated. On further rotation the articles are introduced into the section *CB*, in which the firing process is carried out, and they remain there until the operation is finished, during which time the articles already in the next forward part *BA*, which were previously in *CB*, have time to cool and the articles in the front section are completely cooled, after which the completely-cooled articles are removed in the part *FE*. In the corresponding parts cooling can be accelerated by suitable means. This arrangement therefore unites the advantages of a continuous working with that of a direct base-firing. The heating is produced gradually, and cooling is carried out in the same way until the articles have reached the place where they are removed, in consequence of which arrangement the cracking of even large objects need not be apprehended. This manner of utilizing the firing material is very advantageous and produces an economy of between seventy and eighty per cent. as compared with the old muffle systems.

The new muffle-furnace is especially adapted for burning in colors, and gold on china, earthenware, stoneware, glass, and enamel-iron patterns.

50 I claim—

1. An annular muffle-furnace comprising an annular rotatory support with means for

rotating the same, a heating-chamber at one portion of the annular muffle-furnace arranged below the support, a muffle above the heating-chamber, a preliminary-heating section of the furnace and a cooling-section, substantially as set forth. 55

2. In an annular muffle-furnace, an annular rotatory support comprising a pair of rails connected at intervals by cross-ties, a series of wheels upon which said rails are supported and a floor laid upon said rails on which the articles to be baked are placed, and means for rotating the annular support substantially as set forth. 60

3. In an annular muffle-furnace of the kind described, the combination with the heating-chamber of the stationary supporting-wheels having axles located outside said chamber, the bearings to said axles being arranged on the outside walls of the muffle-furnace, substantially as described. 70

4. An annular muffle-furnace with continuous working and direct base-firing characterized by the arrangement of an annular rotatory support, on which the articles to be treated are placed, said support comprising a pair of annular rails united by cross-ties and provided with a suitable floor, the rails being supported on rollers arranged at intervals on both sides of the furnace and in such manner that the heating-gases produced underneath the muffle and passing around the muffle do not touch the support and the rollers, and means for rotating the traveling support so that the articles to be heated pass successively through the preliminary-heating space, then through the muffle and then through the cooling-space of the furnace, substantially as described. 75 80 85 90 95

5. In an annular muffle-furnace, a heating-chamber *a* a muffle *c*, a rotatory annular bottom support, rails *h*, supporting-wheels *k*, combustion-gas passages *d* and *t*, substantially as described. 95

In testimony whereof I have hereunto set my hand in presence of two subscribing witnesses.

LOUIS HUBERT WILLEM REGOUT.
